ABSTRACT OF THE DISCLOSURE

In a loom a second retaining device for the weft is equipped with a clamping device for receiving a portion of the weft. Said clamping device comprises a presser which is biased onto the weft portion to hold the weft temporarily in position. The presser is moved into and out of an activated position by means responding to the operation of the loom and is released from this position into a clamping position and moved out of the clamping position by means responding to actuation by the shuttle.

This is a divisional application of copending application Ser. No. 487,659, filed Sept. 16, 1965, and now 30 abandoned.

This invention relates to a gripping shuttle loom with a retaining device provided on the gripping shuttle to retain the beginning of the weft when the weft is being inserted into the shed, and a second retaining device which does not move in the direction of the weft and which engages the weft until the weft is bound into the shed. The second retaining device is released by means of a driven member.

Under the present construction of gripping shuttle looms both the release and the subsequent disengagement of a second retaining device is effected by adjusting means which are in positive operative connection with the machine drive. This construction produces an uncertainty in the operation of the second retaining device and there is no proper coordination between the movement of the gripping shuttle and the operation of the second retaining device. If, for example, the gripping shuttle is delayed, the second retaining device may have already been released so that it will no longer engage the beginning of the weft. If, on the other hand, the gripping shuttle arrives too early, the second retaining device will not be ready to engage the beginning of the weft. In either case, it is conceivable that the retaining device of the gripping shuttle will release the beginning of the weft without the weft first being engaged by the second retaining device.

These disadvantages of known gripping shuttle looms are eliminated by this invention in that the release of a second retaining device is made to correspond with the arrival of the gripping shuttle so that a proper sequence of operation between the gripping shuttle and the second retaining device is assured.

This object is achieved, according to the invention, in that the gripping shuttle operates as the release member for the second retaining device. In this manner, a satisfactory transfer of the beginning of the weft from the retaining device of the gripping shuttle to the second retaining device is insured at each weft insertion. This transfer is very important in gripping shuttle looms.

It is another object of the invention to provide a loom in which the gripping shuttle merely represents the release member for the second retaining device, and that

2

the second retaining device is associated with an adjusting member whose movement depends on the machine drive, to place the second retaining device in the inoperative position after it has been released. In contrast to the time of the arrival of the shuttle, the time of the blow of the slay and the time of the change of the shed are constant. It is, therefore, advisable to make the release of the beginning of the weft by the second retaining device independent of the arrival of the shuttle.

It is, therefore, a further object of this invention to provide for the release of the beginning of the weft by the second retaining device to be independent of the shuttle arrival.

The second retaining device can be a mechanical or pneumatic device. Several embodiments of this second retaining device will be described in the specification below.

A more complete understanding of this invention and of the several embodiments which represents the invention will be had by reference to the drawings attached hereto studied in conjunction with the following complete specification and appended claims.

FIGS. 1 to 4 show one embodiment of this invention in which the second retaining device is arranged for movement on the machine frame above the shed.

FIGS. 5 and 6 show another embodiment of this invention in which the second retaining device is similar to the one shown in FIGS. 1 to 4.

FIGS. 7 and 8 show a further modification of this invention similar to that shown in FIGS. 5 and 6.

In general, a gripping shuttle loom uses a gripping shuttle for the insertion of a single weft from both sides. The specific structure of the gripping shuttle is only of secondary importance to the present invention. Thus it may have any desired structure, as for instance the one disclosed in U.S. Patent 2,168,420.

It is to be understood that one second retaining device each is provided on each side of the loom, one being effective when the shuttle leaves the shed on one side, the other when the shuttle leaves the shed on the other side.

The retaining device shown in FIGS. 1 through 4, is positioned above the shed; and just outside the warp edge of the fabric being woven. The presser 11d is in the form of a reed, as shown in FIGURES 1 and 4, and is mounted on a lever 58d which is pivoted about a pin 59d extending parallel to the weft direction. The reed-shaped presser 11d is held in operating or weft retaining position by a torsion spring 60d so designed that it normally urges presser 11d into engagement with the shuttle track 19d and transversely to the direction of movement of the shuttle 1d. (See FIGS. 3 and 4.) Pin 59d is positioned on slide 61d which moves back and forth perpendicularly to the reed in the direction of the double arrow shown in FIG. 1. Slide 61d receives its driving force from a cam disc similar to disc 20i in FIG. 27 shown in the parent patent. For positioning the lever 58d which carries presser 11d, a roll 62d is fixedly mounted on the machine frame. Roll 62d cooperates with the bottom edge of lever 58d which is formed like a cam. During the forward movement of slide 61d lever 58d moves into an operating position shown in FIG. 2 despite the presence of roll 62d, and is moved into the inoperative or weft releasing position shown in FIG. 1 by roll 62d during the return movement of slide 61d. In order to retain the lever 58d in the inoperative position, a latch 63d is provided which is mounted pivotally on a journal 64d. Journal 64d carries a torsion spring 65d which holds latch 63d in the operating position. In this position latch 63d engages the bottom edge of lever 58d (see FIG. 1). The adjusting lever 17d, which cooperates with the adjusting member 18d of the gripping shuttle 1d, is connected for movement with the latch 63d (see FIG. 3). When adjusting member 18d

engages the adjusting lever 17d, latch 63d is moved into the position shown in FIG. 3 and lever 58d, along with the reed-shaped presser 11d, is subject to the influence of the torsion spring 60d. Lever 58d is moved out of contact with the roll 62d by moving slide 61d in the direction toward the reed. Before the gripping shuttle 1d is actuated again slide 61d moves back whereby the roll 62d moves lever 58d of presser 11d upwardly. The upper edge of lever 58d engages a cam 66d disposed on the lower portion of the hook of latch 63d whereby the latch 63d is moved clockwise and locks with the lever 58d. It should be noted that latch 63d has already been returned by means of a compression spring 65d which acts immediately after the adjusting member 18d of the gripping shuttle 1d has passed the adjusting lever 17d.

The adjusting lever 17d is thereby moved into its operating position. To insure that the adjusting lever 17d is moved from the path of the gripping shuttle before the gripping shuttle is actuated, a second cam 67d (see FIG. 3) is provided above the hook of latch 63d. Thereafter, lever 58d is moved upwardly by means of roll 62d, whereby the adjusting lever 17d is temporarily moved into a position to permit the passage of gripping shuttle 1d. A stop pin 68d (see FIG. 3) is mounted on the latch 63d to determine the operating position of the latch 63d and adjusting lever 17d while the slide 61d acts as an abutment for stop pin 68d. This arrangement insures a co-operation between the lever 58d and the cam 66d when lever 58d is moved upwardly by the roll 62d. In the embodiment shown in FIGS. 1 to 4 the presser 11d cooperates with shuttle track 19d as an abutment in the same manner as shown in FIGS. 1 to 5 of the parent patent.

The embodiment shown in FIGS. 5 and 6 corresponds substantially to that shown in FIGS. 1 through 4. Presser 11e, however, is formed by the free end of a spring rod 69e with an initial stress directed both toward the center of the fabric and downward. At the far end of presser 11e, the spring rod 61e is wound to a torsion spring 70e, and is mounted on a bolt 71e of the slide 61e. The free end of the torsion spring 70e is connected to an adjusting spring 72e whereby the presser 11e is held in the lowered operating or weft retaining position as shown in FIG. 6. For the initial stress of spring rod 69e towards the fabric center, the spring rod is bent to the inside at the head of torsion spring 70e. The spring rod 69e engages a guide 73e provided on the right hand side of the slide 61e. A vertical slot 74e and a horizontal locking edge 75e, arranged above and inside slot 74e, are provided in guide 73e (FIG. 5). A supporting member 76e is disposed below spring rod 69e (see FIG. 5). In the inoperative or weft releasing position spring rod 69e presses upon supporting member 76e whereby the presser 11e is in its upper position. The adjusting member 18e is mounted on the upper portion of the gripping shuttle 1e. Before the arrival of gripping shuttle 1e, slide 61e is moved in the direction towards the reed. Spring rod 69e is thus released from the support member 76e and is urged on the locking edge 75e (see FIG. 18). When adjusting member 61e of the gripping shuttle 1e engages the presser 11e, the spring rod 69e is bent outwardly and moves in the range of slot 74e. As soon as adjusting member 18e of gripping shuttle 1e moves under presser 11e, spring rod 69e moves downwardly into slot 74e and assumes the operating position shown in FIG. 6. To return spring rod 69e to the inoperative position, slide 61e is pulled back whereby the supporting member 76e releases the spring rod 69e which in turn moves back into locking edge 75e.

The retention of the weft head is achieved in this embodiment by the free end of spring rod 69e. As shown in FIGS. 7 and 8, this can also be additionally effected by an extension 77f which adjoins the part of the spring rod 69f forming the presser 11f and extends in the weft direction. The extension 77f, is arranged above the upper shed and presses the beginning of the weft over the warps of the shed together with presser 11f against the abutment surface of shuttle track 19f.

It is to be understood that the embodiments herein are shown merely for illustrative purposes and that the invention is not to be limited to these embodiments alone, but rather by the claims appended below.

What is claimed is:

- 5 1. In a loom, a warp in which sheds are formed, a slay and a gripping shuttle movable through the sheds, a clamping device for receiving a portion of a weft from the gripping shuttle upon the latter leaving a shed and for retaining the same until the change of the shed, said 10 clamping device comprising a presser, spring means for biasing said presser downwardly onto the weft portion, lever means carrying said presser and tilttable about an axis parallel to the direction of movement of the shuttle, a slide movable transversely to the path of the shuttle, a holding device carried by the slide for holding said presser in a lifted weft releasing position, a stationary support arranged below said lever means for causing said presser to return to said lifted position during a movement transverse to the path of the shuttle, and means for moving said slide toward the slay to allow said presser to move from said lifted position to a clamping position and for moving said slide in the opposite direction to cause the presser to move to the releasing position.
- 15 2. The arrangement according to claim 1, wherein said holding device includes an arresting lever tiltably supported at said slide.
- 20 3. The arrangement according to claim 2, which includes an adjusting lever connected for movement with said arresting lever and operable to move the latter away from the slay in response to actuation by said shuttle.
- 25 4. The arrangement according to claim 2, wherein said arresting lever comprises a cam by means of which the adjusting lever is tilttable by said lever means out of the 30 path of movement of the gripping shuttle during its lifting movement by said stationary support.
5. The arrangement according to claim 1, wherein said lever means carrying said presser comprises a spring rod which is biased in a direction toward the slay.
- 40 6. The arrangement according to claim 5, wherein said presser is formed by the free end of said spring rod.
7. The arrangement according to claim 5, wherein said holding device comprises a guide connected to the slide and provided with an opening for receiving therethrough said spring rod, said opening including a substantially vertically extending slot and being confined in part by a substantially horizontally extending rest surface with an end stop remote from said slot, said spring rod being biased towards the center of the shed and operable to manually rest on said rest surface against said stop.
- 45 8. The arrangement according to claim 1, wherein said presser and said holding device are arranged within the range of a fabric being woven in the shed, and wherein said presser is adapted to be moved onto the weft portion through the warp threads of the upper portion of the shed.
- 50 9. The arrangement according to claim 8, wherein said presser is formed by the free end of said spring rod and comprises an extension extending across a section of the upper portion of the shed and in the direction of movement of the gripping shuttle.
- 55 10. The arrangement according to claim 8, wherein said presser comprises a comb.
